US0D1018854S

(12) **United States Design Patent** (10) **Patent No.:** **US D1,018,854 S**
(45) **Date of Patent:** **** Mar. 19, 2024**

(54) **TIBIAL PLATE**

(71) Applicant: **New Generation Devices, Inc.**, Naples, FL (US)

(72) Inventor: **Robert Mark Daye**, Medina, OH (US)

(73) Assignee: **Movora, LLC**, Boston, MA (US)

(**) Term: **15 Years**

(21) Appl. No.: **29/829,907**

(22) Filed: **Mar. 8, 2022**

Related U.S. Application Data

(63) Continuation of application No. 17/393,616, filed on Aug. 4, 2021, which is a continuation-in-part of application No. 17/213,114, filed on Mar. 25, 2021, which is a continuation-in-part of application No. 17/026,931, filed on Sep. 21, 2020.

(57) **CLAIM**

The ornamental design for a tibial plate, as shown and described.

DESCRIPTION

FIG. 1 is a perspective view of a tibial plate showing my new design;

FIG. 2 is a right side view thereof;

FIG. 3 is a top view thereof;

FIG. 4 is another perspective view thereof;

FIG. 5 is a bottom view thereof;

FIG. 6 is a front view thereof;

FIG. 7 is a right side view thereof; and,

FIG. 8 is a top view thereof.

The broken lines in FIGS. 4-8 are included for the purpose of illustrating environment and form no part of the claimed design.

1 Claim, 8 Drawing Sheets
